UNITED STATES PATENT OFFICE

EDWARD C. THRASHER, OF DETROIT, MICHIGAN, ASSIGNOR TO PARKE, DAVIS & COMPANY, OF DETROIT, MICHIGAN, A CORPORATION OF MICHIGAN

DESIGN FOR A CAKE OF SOAP

Application filed June 8, 1931. Serial No. 40,132. Term of patent 14 years.

To all whom it may concern:

Be it known that I, EDWARD C. THRASHER, a citizen of the United States of America, residing at Detroit, in the county of Wayne and State of Michigan, have invented a new, original, and ornamental Design for a Cake of Soap, of which the following is a specification, reference being had therein to the accompanying drawings forming a part thereof, wherein

I claim:

The ornamental design for a cake of soap substantially as shown.

EDWARD C. THRASHER.
